UNITED STATES PATENT OFFICE.

EGBERT H. GOLD, OF SHELBY, INDIANA.

AUTOMATIC SUPPLY-REGULATOR.

SPECIFICATION forming part of Letters Patent No. 758,437, dated April 26, 1904.

Application filed January 26, 1904. Serial No. 190,708. (No model.)

To all whom it may concern:

Be it known that I, EGBERT H. GOLD, a citizen of the United States, residing at Shelby, in the county of Lake and State of Indiana, have invented certain new and useful Improvements in Automatic Supply-Regulators, of which the following is a specification.

The object of my invention is to provide means for automatically regulating the supply of a heating medium to a radiating system, said means being actuated by the condition of the heating medium at a point adjacent to the outlet of the radiating system. These and such other objects as may hereinafter appear are attained by the devices shown in the accompanying drawings, in which—

Figure 1 indicates diagrammatically and in perspective the heating system of a car fitted with my apparatus, and Fig. 2 is a sectional detail through my device.

A indicates the floor of a car; B, the train-pipe; C, the supply-pipe leading from the train-pipe to my apparatus; D, the supply-pipe leading from my apparatus to the radiating system of the car; E, the radiating-pipes; F, the return-pipe leading from the radiators to my control device; G, the drip-pipe discharging to the atmosphere, and H the thermostatic casing.

I indicates the casing containing the principal parts of my apparatus.

J is a hand-operated feed-valve.

The casing I is provided with a rigid diaphragm I' and a flexible diaphragm 2, by which it is divided into an inlet-chamber 3, an intermediate chamber 4, and an outlet-chamber 5. Leading into the inlet-chamber 3 is a port 6, which communicates with the feed-pipe C and is provided with a valve-seat 7.

Mounted within the inlet-chamber 3 is a valve 8, adapted to seat upon the valve-seat 7 and provided with a stem 9, which extends through the permanent diaphragm 1 and is attached to the flexible diaphragm 2.

Mounted upon the valve-stem 9 is a helical spring 10, which normally holds the valve 8 unseated from the valve-seat 7. Upon that portion of the valve-stem 9 which extends within the inlet-chamber 3 is a collar 11.

Mounted upon the valve-stem 9 between

the collar 11 and the diaphragm 1 is a washer of packing material 12.

In the position of the parts shown in Fig. 2 the expansion of the helical spring 10 draws the collar 11 on the valve-stem 9 tightly against the packing-washer 12 and firmly clamps the packing-washer 12 between the collar 11 and the permanent diaphragm 1, thus making steam-tight the passage through the diaphragm 1, through which the valve-stem 9 projects.

Steam entering the device through the supply-pipe C enters the inlet-chamber 3, passes thence through the pipe D to the radiating-pipes, whence it returns through the pipe F to the outlet-chamber 5 within the casing I. The port between the outlet-chamber 5 and the drip-pipe G is provided with a valve-seat 13, adapted to be closed by a valve 14, operated by a thermostatic steam-trap of familiar construction.

As the radiating-pipes E become filled with live steam the live steam passing through the outlet-pipe F fills the outlet-chamber 5 and passing therefrom through the drip-pipe G and around the diaphragm 15 within the diaphragm casing H will expand the diaphragm, thereby closing the valve 14 against the valve-seat 13, whereupon the further admission of steam to the radiating system through the supply-pipe C will create a pressure within the system, provided the radiating-pipes E are filled with live steam. When this pressure reaches the outlet-chamber 5, it will expand the flexible diaphragm 2, thereby carrying the valve-stem 9 against the spring 10 and seating the valve 8 upon the valve-seat 7, with the result that the supply of steam to the radiating system is immediately shut off.

The steam within the radiating-pipes condensing will cause a flow of the water of condensation into the outlet-chamber 5 and will cause a reduction of pressure within the chamber 5, with the result that the valve 8 will reopen to allow the admission of sufficient steam to replace the steam which has so condensed. The water of condensation within the chamber 5 will meanwhile be taken care of by the contraction of the thermostat 15 and the consequent opening of the valve 14.

In actual operation the apparatus so adjusts itself that ordinarily the valve 8 will be slightly open, so as to admit just enough live steam to compensate for condensation within the system and keep the radiating system supplied with live steam, while the valve 14 will adjust itself to be open just enough to take care of the water of condensation as it flows into the chamber 5.

While in the drawings I have shown only enough of the apparatus to disclose the construction and operation above described, it will be readily understood by those skilled in this art that any well-known means can be adapted to this device for regulating the tension upon the diaphragm 2, and thereby regulating the pressure at which the diaphragm 2 will be operated to close the valve 8.

While I have shown my invention embodied in what I at present consider its preferred form, it will be understood that the details of construction may be considerably varied without departing from the spirit of my invention, and my invention contemplates such variations from the structure as shown and described.

My apparatus is especially adapted for use in connection with a radiating system, such as that commonly now used in railway-cars, in which, for example, a radiating system of five hundred or six hundred feet of pipe of small diameter and necessarily having many turns, including descending and rising pipes, through which the heating medium must flow and in which there is a great amount of friction and rapid radiation and condensation. In using low-pressure steam as the heating medium in such a system it is important that the radiating system shall at all times be filled with live steam, because the comparatively low temperature of low-pressure steam, which makes it desirable for heating a living-room, such as the inside of a car, also makes it necessary to have the radiating system filled with this steam at all times, for if any considerable part of the radiating system be filled with cool air or water of condensation the heating efficiency of the steam will be very appreciably reduced. With my apparatus the supply and discharge ends of the radiating system are so related to each other that the rate of supply is so governed by the condition within the circulating-pipes, near the discharge end thereof, that the pipes will be at all times filled with live steam at low pressure, notwithstanding the fact that the supply is drawn from a high-pressure conduit, and at the same time water of condensation is freely discharged. It will therefore

be understood that I do not, broadly, claim any system in which the pressure within the radiating system is utilized to control the supply of heating medium to the radiating system, even when used in connection with automatic means for providing for the discharge of the water of condensation; but my invention does relate to the apparatus herein claimed by me, wherein a diaphragm-motor actuated by pressure within the radiating system, adjacent to the discharge end thereof, is utilized, in connection with a thermostatic trap connected with the discharge end of the radiating system, to automatically control the supply of the heating medium, so as to at all times keep the radiating-pipes filled from end to end with live steam at substantially atmospheric pressure.

I claim—

1. In a heating system, the combination with a system of radiating-pipes leading at one end to the atmosphere, of a valve, arranged at the other or inlet end of the radiating-pipes to control the flow of the heating medium into said pipes, a thermostatic trap arranged to automatically open and close the outlet from the discharge end of the pipes to the atmosphere, and a diaphragm - motor mounted within a chamber communicating with said pipes adjacent to the outlet end thereof, said diaphragm-motor being arranged to automatically operate said inlet-valve.

2. In a heating system, the combination with a system of radiating-pipes communicating at their discharge end with the atmosphere, and provided with an inlet-chamber communicating with their inlet end, of means for supplying a heating medium to said radiating-pipes through said inlet-chamber, a valve mounted in said inlet-chamber and arranged to control the flow of the heating medium therethrough, a thermostatic trap arranged to control the opening from the discharge end of said pipes to the atmosphere, a diaphragm-motor arranged within a chamber communicating with the radiating-pipes adjacent to the discharge end thereof, and connections between said diaphragm-motor and said valve, all so arranged that when actuated by pressure within said circulating system, adjacent to the discharge end thereof, said diaphragm-motor will move said valve in a direction to shut off the flow of the heating medium into the inlet end of said radiating system.

EGBERT H. GOLD.
